UNITED STATES PATENT OFFICE.

GEORG ULLRICH, OF MAGDEBURG, GERMANY.

APPARATUS FOR THE MAGNETIC SEPARATION OF ORES AND OTHER MATERIAL.

1,072,277.

Specification of Letters Patent.

Patented Sept. 2, 1913.

Application filed January 17, 1912. Serial No. 671,570.

To all whom it may concern:

Be it known that I, GEORG ULLRICH, a subject of the King of Bavaria, and resident of Magdeburg, German Empire, have invented certain new and useful Improvements in or Relating to Apparatus for the Magnetic Separation of Ores and other Material, of which the following is a specification.

This invention relates to apparatus for the magnetic separation of ores and other material, and constitutes an improvement in or a modification of the apparatus described in the specification of my prior application Serial No. 445852 filed July 29, 1908. In order to carry the separation of the material as far as practicable with the apparatus referred to above it is necessary that the lines of force passing from one magnet to an adjacent magnet should pass through the rotating armature and flow therein without meeting unnecessary resistance. The dimensions of the armature in cross-section must be calculated accordingly and it has been found that in the above type of apparatus, the cross sectional area of the armature must be at least half as great as that of the magnet core. This renders the dimensions and the weight of the armature relatively large and therefore a correspondingly large mechanical effort is necessary for rotating the same. It has also been found in the above type of apparatus that highly magnetic material adheres firmly to the rotating armature even outside the magnetic field so that the carrying away of the magnetic material after separation is impeded.

The present invention has for its object to economize in the expenditure of mechanical effort and to facilitate the carrying away of the magnetic material after separation.

According to this invention the magnetizable rings serving as the armature and counter-pole for the lower magnets instead of being rotatable are stationary and the carrying away of the separated magnetic material is effected by a rotating member arranged between the armature rings and the lower fixed magnets. The said rotating member is mounted coaxially with the rings and may be axially adjustable. Preferably the cross section of the rotating member is such that the contour thereof corresponds with the contour of the lower part of the armature rings.

One way of carrying the invention into

effect is illustrated in the accompanying drawings, in which—

Figure 1 is a vertical section of the improved apparatus. Fig. 2 is a partial plan of Fig. 1, and Fig. 3 is a development of two magnets and the corresponding armature element in side elevation viewed in the direction indicated by the arrow in Fig. 2; the armature element being however of modified form. Fig. 4 shows in vertical section a modified form of the apparatus and Fig. 5 a plan view of Fig. 4 partly in section on line A—B of Fig. 4 and with the rotatable parts turned 45° from their position in Fig. 4.

A plurality of magnets 1 provided with a common core are arranged in a circle around a stationary axis and carry pole pieces 2 each of which is energized by a coil 3. A central shaft 4 the axis of which coincides with the axis of the magnets is adapted to be rotated by suitable gearing such as that shown.

Double angled supports 5 are fixed by their lower branches to the magnets 1 their upper branches carrying concentric magnetizable rings 6 which serve as the armature and counter pole for the magnets 1 and can be adjusted axially by means of screws 7. This axial adjustment of the armature rings 6 can be effected independently of each other in the example shown. The cross sectional area of the armature rings 6 decreases toward the magnets 1 owing to its tapering formation.

Below the armature rings and between the latter and the magnets 1, a member 8 is provided which in the example illustrated is constituted by a corrugated disk. The member 8 which serves for carrying the separated magnetic material, is suspended coaxially with the armature rings 6 on a disk 9 which rotates with the shaft 4, and is adjustable axially by means of screws 10. The rotating member 8 is arranged in such a manner that each depression of its corrugations is opposite to the tapered end of an armature ring 6.

In the example shown a hopper 11 is arranged on the disk 9 and is connected with the shaft 4, so as to rotate therewith and conveyer channels 12 lead from the hopper into the several magnetic fields and below the member 8.

The operation of this apparatus is as fol-

lows: The material to be separated is delivered to the hopper 11 from which it passes through the conveyer channels 12 into the magnetic fields. On the passage of 5 the material through the field gap of the several magnetic fields, the magnetic particles according to their permeability are separated into the zones formed by the several armature rings 6. The non-magnetic 10 material passes along the conveyer channels 12, while the magnetic material adheres firmly to the lower face of the rotating member 8 and is thus carried outside the magnetic fields, whereupon it falls in the 15 space between each pair of adjacent magnets 1. In order to eliminate any magnetic action of the armature rings 6 when passing over the said spaces and thus prevent the magnetic material from being carried too 20 far, the armature rings 6 may be shaped as shown in Fig. 3 wherein they are provided with recesses 13 of the same width as that of the space between two adjacent magnets.

The construction of the apparatus is not 25 confined to the example described above and illustrated in Figs. 1, 2 and 3; on the contrary a large number of other constructions both for the apparatus as a whole and for its several parts can be advantageously 30 adopted. For example it is not absolutely necessary that the rotating carrying member 8 should be corrugated as it might be given the form of a plain disk. It is, however, advantageous for the shape of the carrying member 8 to correspond to the contour of the lower parts of the armature rings 6. The number of the armature rings 6 depends upon the number of the materials to be separated, and the adjustment of the 35 said rings may be such that several or all of them can be adjusted simultaneously. The arrangement and construction of the carrying member 8 can also be modified in such a manner that it is adjustable in relation to 40 each of the zones formed by the armature rings 6, so that it can be adjusted independently of or simultaneously with respect to several of or (as shown) all of the zones.

In place of continuous armature rings, 45 separate ring elements can be employed in which case they are fixed over each of the lower fixed magnets to a common supporting member adjustable relatively to the magnets. This arrangement renders it possible to adjust the zone graduations at the 50 same time to different sizes in the several magnetic fields. By this means the additional advantage is obtained that in the case of a magnetic separator with a number of working or operating points it is 55 possible to treat several kinds of material presenting magnetic properties differing widely one from the other. Such a separator is shown by way of example in Figs. 4 and 5. In a circle about a stationary axis,

are fixedly arranged a plurality of magnets *b* provided with a common core *a*, which are excited by a winding *c*. The magnets possess each two superposed poles *d* and *e*. The upper poles *d* are provided with a plurality 70 of magnetizable lamellæ *f*, adjustable in the vertical direction through means of the screws *g* and arranged one behind the other in the direction of the introduction of the values, which lamellæ are sharpened at their 75 lower portions. By the adjustment of the lamellæ each of the individual magnetic fields can be subdivided into a plurality of zones of different density. In the middle 80 of the magnetic circuit is mounted an upright shaft *h*, which can be set in rotation by any desired driving means. The shaft *h* carries on its upper end a cross arm *i* upon which is secured with vertical adjustment, an extracting body *k*, arranged between the 85 superposed poles *d* and *e* of the magnet *b*. The annular extracting body has a suitable wave-formed section, the dimensions and division of the waves of which correspond to the lower portion of the section of the 90 ring-piece. For introducing the magnetic values, any desired delivering apparatus *m* will serve, which will direct the separating values beneath the extracting body *k* between the pairs of poles *d* and *e* through the 95 field-gap.

The mode of operation is as follows:— The separating values are conducted by the delivery apparatus *m* into the individual magnetic fields. By the passage of the values through the field gap, the magnetic particles also separate according to their permeability in the zones composed by the individual lamellæ *f*. While the magnetic values are conducted inwardly by the delivery apparatus *m*, the magnetic values stick fast to the under surface of the extracting body *k*, are carried out of the magnetic fields, and fall in the intermediate space between two adjacent magnets *b*. It is immaterial how the introduction of the separating values and the further conducting of the magnetizable values take place.

The number of the plate-shaped bodies or lamellæ *f* arranged upon the upper pole *d*, 115 is determined in each instance, according to the number of the materials to be separated. The adjustability of the lamellæ *f* can be so determined that several or all may be adjusted simultaneously.

Having thus described my invention, what I claim as new therein and desire to secure by Letters Patent is:

1. In a magnetic separator, means for producing a plurality of magnetic fields in 125 a circle about a vertical axis, in each magnetic field two stationary poles of which the upper pole comprises lamellæ adjustable vertically and independently of each other, said lamellæ being downwardly sharpened, 130

for the purpose of providing, in each magnetic field, a plurality of single adjustable zones and an extracting body revolving between said poles, said extracting body being 5 corrugated to conform in shape with the sharpened part of said lamellæ, and means for conveying the material to be separated between the upper and the lower poles.

2. In a magnetic separator, means for producing a plurality of magnetic fields in a 10 circle about a vertical axis, in each magnetic field two stationary poles of which the upper pole comprises lamellæ adjustable vertically and independently of each other, said 15 lamellæ being downwardly sharpened, for the purpose of providing, in each magnetic field, a plurality of single adjustable zones and an extracting body revolving between said poles, and means for conveying the material 20 to be separated between the upper and the lower poles; said extracting body having an undulated radial section corresponding to the sharp pointed lamellæ.

3. In a magnetic separator, a plurality of 25 stationary lower poles arranged in a circle about a vertical axis, a plurality of non-revolvable upper pole rings concentrically arranged about said axis above said lower poles, a common carrying frame for said 30 pole rings, a revoluble extracting body beneath said pole rings, said extracting body being corrugated to conform in shape with the sharpened part of said lamellæ; and means for conveying the material to be separated 35 in between the poles; said pole rings being axially adjustable independent of each other and each being provided with a sharp downward edge.

4. In a magnetic separator, a plurality of 40 stationary lower poles arranged in a circle about a vertical axis, a plurality of non-revolvable upper pole rings concentrically arranged about said axis above said lower poles, a common carrying frame for said 45 pole rings, a revoluble extracting body beneath said pole rings; and means for conveying the material to be separated in between the poles, said pole rings axially adjustable independent of each other and each 50 being provided with a sharp downward edge, and recesses being formed on the under side of said extracting body between said rings.

5. In a magnetic separator, a plurality of 55 stationary lower poles arranged in a circle about a vertical axis, an upper stationary pole above each of said lower poles, said upper pole comprising a plurality of magnetizable plate-like elements sharpened 60 downwardly, said elements being vertically adjustable relative to each other and to said upper pole and being arranged one behind the other in the direction of the introduction

of the material to be separated; a common carrying member for said elements conducting the magnetic forces, a common extracting body revolving beneath all of said elements and means for conveying the material to be separated beneath said extracting body, said extracting body being corrugated 65 to conform in shape with the sharpened part 70 of said lamellæ.

6. In a magnetic separator, relatively fixed upper and lower magnetic rings, vertical electromagnets having one ring for their 75 yoke and the other ring for their armature, from the latter of which rings the ends of the cores of the magnets are separated by an air gap, the magnetic circuits being through adjacent cores and the two rings and across 80 the gaps, conveyors arranged in the gap to transfer the material to be separated between the axial portion of the rings and places exterior thereto, and a collecting apron rotatable in the gap and above the 85 conveyer.

7. In a magnetic separator, a series of fixed vertical electro-magnets arranged symmetrically about a common axis, an armature separated from the free ends of the 90 cores by an air-gap, the armature and the said free ends of the cores forming opposing magnetic poles, one of which is provided with arc shaped corrugations facing the other, conveyors arranged in the gap to 95 transfer the material to be separated between the axial portion of the rings and places exterior thereto, and a collecting apron rotatable in the gap and above the 100 conveyers, the apron having corrugations corresponding to the said arc shaped corrugations.

8. In a magnetic separator, means for establishing a substantially vertical flow of 105 flux through an air gap, means for conveying material through such gap, and a corrugated apron movable at right angles to the conveyed material and having wedge-shaped ribs concentric with the axis of rotation of the apron.

9. In a magnetic separator, means for establishing a substantially vertical flow of flux through an air gap, the upper pole of such gap having wedge-shaped concentric ribs, means for conveying material through 115 the gap, and an annular corrugated apron movable at right angles to the conveyed material, the corrugations of the apron substantially fitting the ribs of the pole.

The foregoing specification signed at 120 Magdeburg this 21st day of December, 1911.

GEORG ULLRICH.
